(57) **CLAIM**

The ornamental design for an electric hot pot, as shown and described.

DESCRIPTION

FIG. 1 is a top perspective view of an electric hot pot showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top perspective view of an electric hot pot shown in another configuration of use.

The broken lines in the drawings depict portions of the electric hot pot that form no part of the claimed design.
